UNITED STATES PATENT OFFICE.

JOHN P. EUSTIS, OF NEWTON, MASSACHUSETTS.

DESIGN FOR A SOAP-DISH.

No. 39,774.

Specification for Design.

Patented Jan. 19, 1909.

Application filed October 29, 1908. Serial No. 460,165. Term of patent 7 years.

To all whom it may concern:

Be it known that I, JOHN P. EUSTIS, a citizen of the United States of America, residing at Newton, in the county of Middlesex and State of Massachusetts, have invented a new, original, and ornamental Design for Soap-Dishes, of which the following is a specification, reference being had to the accompanying drawings, forming part thereof, and in which—

Figure 1 is a perspective view, and Fig. 2 is a front elevation of the soap dish.

I claim—

The ornamental design for soap dish, substantially as shown.

JOHN P. EUSTIS.
